UNITED STATES PATENT OFFICE.

JOHN F. INGHRAM, OF ALLEGHENY, ASSIGNOR TO HIMSELF AND JOHN H. NOBLE, OF VERONA, PENNSYLVANIA.

SEAL-LOCK.

SPECIFICATION forming part of Letters Patent No. 289,417, dated December 4, 1883.

Application filed July 26, 1883. (Model)

To all whom it may concern:

Be it known that I, JOHN F. INGHRAM, of the city of Allegheny, in the county of Allegheny and State of Pennsylvania, have invented a new and useful Improvement in Seal-Locks; and I do hereby declare the following to be a full, clear, and exact description thereof.

My invention relates to an improvement in seal-locks for railroad-cars; and it consists in a sliding bolt for securing the hasp, and a sliding collar or dog, in combination with a disk-seal provided with a shank, on the end of which is a button adapted to engage with the bolt, and a case for holding the seal, so arranged that when the bolt is lowered and the seal is placed in position the bolt cannot be released nor the seal removed without breaking the button from the shank of the seal.

Heretofore in seal-locks, where frangible seals have been used, in most cases it has been necessary to break, and thereby destroy, the face of the seal in order to open the lock. This difficulty is avoided by my invention, as by opening the lock the button is cut or broken off, leaving the face or disk portion of the seal perfect and unbroken, so that it can be filed away for reference.

I will now describe my invention so that others skilled in the art may manufacture and use the same, reference being had to the accompanying drawings, forming part of this specification, in which—

Figure 1 is a front elevation of my improved seal-lock. Fig. 2 is a vertical sectional view of the same, showing the bolt lowered and the seal in position and secured. Fig. 3 is a vertical sectional view of the same, showing the bolt raised. Fig. 4 is a horizontal sectional view of the same, through the shank of the seal at x x , Fig. 2. Fig. 5 is an elevation of the sliding collar which secures the seal in place. Fig. 6 is a front elevation of a modified form of my improved seal-lock. Fig. 7 is a front elevation of the same, the front plate being removed and the bolt raised. Fig. 8 is a like view, the bolt being lowered; and Fig. 9 is a vertical sectional view through the shank of the seal.

Like letters of reference indicate like parts wherever they occur.

In both the form of lock shown in Fig. 1 and the modified form shown in Fig. 6 the lock consists of a sliding bolt adapted to secure the hasps, and arranged in a lock case or frame, the bolt being provided with a recess or slot for engaging with the button on the shank of the seal, and a collar or dog for locking the seal when placed in position.

In the drawings, a represents the round bolt which slides up and down in the case b . At the top of the bolt a is an arm, c , and in the side of the bolt, inside of the case b , is an inclined slot or recess, d , which, when the bolt a is lowered, comes under the opening e in the case b . In the face-plate of the lock-case b is a cavity, e , similar in size to the seal used. In the center of this cavity e is the opening e' , leaving the rabbet or stop f , so as to allow the disk portion of the seal to be inserted in the face-plate of the lock-case without passing through the opening. On the bolt a , inside of the case b , below the slot or recess d , is a lug, g , and on the inside of the face-plate of the case b , near the bottom thereof, is a lug h . Inside of the case b , around the bolt a , is a sliding collar, i , having a slit, k , extending from the lower end upward to about the middle of the collar. This slit is of a greater width than the thickness of the shank x of the seal x , and of a less width than the head or button y on the end of the shank. Inside of the case b , on the rear face thereof, is a slot, m , which engages with the lug g when the bolt is raised and turned, and thereby holds it in this position. Below the case b are the thimbles nn , over which the hasp passes, and is secured by the bolt being lowered through the thimbles and over the hasp. The seal x has a disk face, from the rear side of which extends a shank, z , at the end of which shank is a button, y . This seal may be formed of any suitable material—such as cast-iron, lead, white-metal, or other substance that is either frangible or capable of being cut by the action of the bolt, so as to remove the button from the shank.

In the operation of these devices, the bolt a being raised and held by the lug g on the bolt a , engaging with the slot m on the rear face of the case b , as shown in Fig. 3, the car-door is locked and sealed as follows: The hasp,

which is not shown in the drawings, is placed over the thimbles n n . The seal is then inserted in the cavity e , the button and shank of the seal passing through the opening e' , the button coming in contact with the bolt a as the collar is held up out of the way by the lug g . The bolt is then turned partially by means of the arm c , which relieves the lug g from the slot m , and the bolt is lowered or depressed, so that the end thereof shall enter the thimbles n n , and thereby secure the hasp. The sliding collar i , however, remains at the top of the case, as it is held by the button y of the seal. The bolt a is then turned farther on its axis by means of the arm c , which brings the lug g on the bolt a under the lug h on the face-plate of the case b , as shown in Fig. 2. This locks the bolt a , so that it cannot be raised without first being turned on its axis. At the same time the slot or recess d in the bolt a is brought opposite the opening e' , and the button y on the end of the shank of the seal enters the slot, when the collar i , being released, falls down, so that the shank z of the seal is in the slit k , as shown in Fig. 4. This effectually locks and seals the car-door. The seal cannot be removed from the opening e without breaking off the head or button y , as the head is larger than the width of the slit k , and as the opening e' is closed by the seal the collar i cannot be raised until the seal is removed. Nor can the bolt be raised so as to free the hasp without breaking the button from the seal, as in order to raise the bolt it is first necessary to turn it on its axis in order to free the lugs g and h from each other, and this turning motion breaks the button off the shank, as it is situated in the slot d .

In order to unlock the car-door, the arm c is turned so as to release the lug g , and thereby the button y is broken or cut from the shank of the seal x . The seal is then removed and the bolt is raised to its former position, where it is held by turning the bolt so that the lug g will engage with the slot m . When the bolt a is turned and the button broken, the inclined slot d comes opposite a groove, p , in the inner face of the collar i . Through this groove the button drops into the bottom of the case b and out by the opening g .

In order to prevent the seal being placed in position in its cavity e , in the face-plate of the case b , after the lock has been opened and the button cut off the shank of the seal, so as to give the appearance of the lock not having been opened, I place a spring, r , within the case b , its lower end being secured to the case and its upper end bent at right angles, so as to project through a small opening in the face-plate in the rabbet f , at one side of the opening e' , and in the cavity or receptacle for the disk of the seal. When the disk of the seal is inserted in the cavity e , it forces back the spring and admits of the button entering the slot d in the bolt a , and of the seal being locked by the sliding collar i ; but if the button is broken off it is impossible for the disk of the

seal to be held in place, as the spring will force it out, unless it is held in place by the sliding collar and button, as before described. This 70 spring is also shown in the modified form of my invention.

In the modified form shown in Figs. 6, 7, 8, and 9 the bolt a' , instead of being round, is flat, and passes through correspondingly 75 shaped thimbles n' n' . In the case b' , between the face-plate and the bolt a' , is a dog, i' , which is pivoted in the case b' by the pin c' , extending from the face-plate. In the bolt a' is an inclined slot or recess, d' , and in the edge of 80 the dog i' , below the pivotal point, is a slot, k' , slightly curved, which slot is less in width than the size of the slot d' . On the face of the bolt a' , below the slot d' , is a lug, g' . In the face-plate of the case b' is a cavity, e' , for the 85 reception of the disk of the seal, and an opening, e' , similar to the opening e' in the other form of lock. Secured to the face-plate of the case is a spring, r' , the other end of which is bent, and projects through an opening in the rabbet f' . In the side of the dog i' , just below the slot k' , is a notch, l , and in the lower part of the case b' is an opening, m' .

In the operation, the bolt a' being raised and held in position by the notch m' in the dog i' , 95 engaging with the lug g' , as shown in Fig. 7, the car-door is locked and sealed by moving the dog so as to relieve the bolt. The bolt is then partially lowered, and the button on the shank of the seal is inserted through the opening e' . The bolt is then depressed until the end thereof passes through the thimbles n' n' , and the button y enters the slot d' , the dog i' , being then released, drops, so as to secure the shank z in the slot k' , and the end of the dog 100 comes over the lug g' . This locks and seals the door of the car, for the seal being secured in the cavity e' , and held by the button y , which is larger in size than the width of the slot k' , the opening e' is closed thereby, and 105 the dog i' cannot be moved so as to release the shank of the seal from the slot, and as the dog i' engages with the lug g' on the bolt a' the bolt is prevented from being drawn from the thimbles n' n' .

In order to unlock the car-door, the button is broken from the shank of the seal by driving the bolt a' downward by a blow on the top thereof. The seal is then easily removed from the opening and the dog swung to one side, 110 releasing the lug g' and allowing the bolt to be raised to its first position. When the dog is swung to one side, the broken button falls out of the inclined slot d and through the opening m' in the bottom of the case b .

The face of the seal x being uninjured, when removed from the lock by the spring r , may be filed away for reference.

When the bolt is locked, as described, the openings m' and q are closed by the lugs g' and g . Although but one projecting button on the seal is mentioned, I do not desire to limit myself to this number.

Having thus described my invention, what

I claim, and desire to secure by Letters Patent, is—

1. A lock consisting of a movable bolt and a lug, dog, or catch for preventing the withdrawal of the bolt when in a locked position, in combination with a seal which enters the case of the lock, and prevents the bolt being released from its catch without first breaking the stem of the seal, and a device for engaging the stem of the seal to prevent its withdrawal from the lock-case until the stem is broken, substantially as described.

2. In a seal-lock having a movable bolt and a catch for locking the bolt independently of the seal, a frangible seal having an internally-projecting stem which enters a cavity in the bolt when the bolt is in a locked position, so that the bolt cannot be moved to disengage it from its catch without breaking the stem of the seal, substantially as specified.

3. In a seal-lock, a movable bolt, in combination with a seal having an internally-projecting button, and adapted to engage with the bolt, a device for locking the seal, and a lug or lugs for locking the bolt, substantially as specified.

4. In a seal-lock having a cavity for the reception of the seal, and devices for securing or locking the seal therein, a spring for ejecting or releasing the seal from the cavity when the seal is released from the securing or locking devices, substantially as and for the purposes described.

In testimony whereof I have hereunto set my hand this 16th day of July, A. D. 1883.

JOHN F. INGHRAM.
